UNITED STATES PATENT OFFICE.

JOHN MILLS, OF WYOMING, NEW JERSEY, ASSIGNOR TO WESTERN ELECTRIC COMPANY,
INCORPORATED, OF NEW YORK, N. Y., A CORPORATION OF NEW YORK.

DUPLEX RADIO SYSTEM.

Application filed December 24, 1920. Serial No. 432,969.

To all whom it may concern:

Be it known that I, JOHN MILLS, a citizen of the United States, residing at Wyoming, in the county of Essex, State of New Jersey, have invented certain new and useful Improvements in Duplex Radio Systems, of which the following is a full, clear, concise, and exact description.

This invention relates to a duplex radio transmission system.

An object of the invention is to provide a means for duplex carrier wave transmission employing the same carrier frequency for both directions.

Another object of the invention is to provide a method of and means for preventing side tone interference at a receiving station due to simultaneous reception of the desired signal wave and the wave from the related or local transmitting circuit.

Further objects will occur as the description of the invention proceeds, wherein, for example, it will be shown that the discrimination sought is independent of the direction of the communicating station, and also that the correspondence between the balanced and balancing waves is secured in a simple manner by deriving them from a common origin.

The method of the invention has application to duplex radio operation. A duplex radio station may, in a usual case, comprise detached transmitting and receiving units housed in separate structures. These units may be conjugately connected to the terminal circuits of a line connecting the units to a central station in which are coordinated the transmitted and received signals. The central station may be, in a practical case, the exchange of the local telephone system so that any subscriber to the telephone system can be connected to the radio system, although the arrangements, in general, are equally applicable to telegraphy.

The conjugate relation of the transmitting and receiving circuits to the common line effectually prevents the outgoing energy from the common line entering the receiving circuits. The condition of use of the same high frequency for the two directions of transmission requires that the receiving circuits be tuned to the frequency of the waves sent out from the related or local transmitting unit, and accordingly these cir-

cuits may receive a portion of the energy sent out from the transmitting unit and give an undesirable side tone in the receiver. Further, by reason of the closed high frequency path constituted by the transmitting circuits, transmitting antenna, receiving antenna, receiving circuits and the circuit connecting the receiving and transmitting circuits, any unbalance in this connecting circuit causes a tendency to sing with attendant undesirable effects on the function of the transmitting and receiving circuits. The invention provides means to avoid such effects by preventing the energy of the waves incident on the receiving antenna from the related or local transmitting antenna from flowing in the receiving circuits. The invention accomplishes the additional function of preventing interference between transmitted and received signals which would otherwise occur in the event of simultaneous operation of the system in both directions.

The invention contemplates balancing out the portion of the transmitted wave that is incident on the related or local receiving antenna by means of an auxiliary wave simultaneously transmitted therewith. Auxiliary antennæ, which may be small in size as compared with the main antennæ, are used to transmit and receive the auxiliary wave and means are provided at the receiving station to equalize and oppose the two waves. The normally received wave from the distant station is unaffected. The condition of complete balance requires that the opposed waves must be identical in all respects. This requirement is satisfied, in one arrangement of the invention, by using a common modulating wave for the main and auxiliary waves at the transmitting station, no necessary relation existing between the frequencies of the respective carrier waves, and effecting a balance between the detected modulating components. In an alternative arrangement effective for telegraph transmission, the balance is effected between high frequency modulated components. The requirement to be satisfied in this alternative arrangement is accordingly more difficult than in the former case since both the carrier frequency and modulating characteristics of the opposed waves must be identical. The desired re-

sult is accomplished by deriving the two carrier frequencies from a common source, one frequency being a harmonic of the other. This insures a fixed relationship between the carrier frequencies and the requirement may accordingly be completely satisfied by the use of a frequency-multiplying device and selective circuits at the receiver to equalize the frequencies of the main and auxiliary waves. In other respects the two arrangements are similar.

The invention provides for the balancing out of the interfering wave at the receiving station without special regard to the relative directions of the distant and related transmission stations. Further, the transmission of the auxiliary wave by radiation results in the advantage, as compared with wire transmission, that a balance can be more simply and easily effected, inasmuch as the effects of differential attenuation and of phase shift are substantially avoided.

For a further disclosure of the invention, reference is made to the detailed description which follows, together with the appended drawing, in which Fig. 1 shows in schematic form, a circuit arrangement embodying the invention at one of a pair of similar communicating stations. Fig. 2 shows a more specific type of the system disclosed in Fig. 1, and Fig. 3 shows the system of Fig. 2 with the circuits of the several elements of the system disclosed in detail.

In the drawing, the reference letters applied to the several parts are chosen with reference to the conventional terms descriptive of their function. For example, amplifiers, detectors, modulators and filters have been designated, respectively, by AM, D, M and F.

Referring to Fig. 1, 1 indicates, generally, a balanced or hybrid coil arrangement of a well known type interconnecting the respective outgoing and incoming lines 2 and 3 with the line L which may lead to a central control station or to an exchange of a local telephone system. By the arrangement shown, a local subscriber, for example, may transmit speech currents over lines L and 2 to the modulators M₁ and M₂, and may simultaneously receive from receiving antenna A'₁.

M₁ and M₂ are modulators of any type, on the input circuits of which currents of carrier frequencies are impressed by generators G₁ and G₂, respectively, of convenient type and size. To insure that the modulated carrier waves transmitted by antennæ A₁ and A₂ are identical as to their modulation components, the carrier waves impressed on the input circuits of the two modulators are modulated by currents from the same telephone line L. To insure the complete separation of output energy transmitted from the modulators, the carrier frequencies

are chosen widely different. The transmitting station transmits the two waves with markedly different amounts of radiated power, since antenna A₁ is designed to work with the corresponding receiving circuit at the distant station, while antenna A₂, with its associated circuits and apparatus needs only to have sufficient energy capacity to transmit efficiently to the auxiliary antenna A'₂ of the local receiving station.

The waves radiated from antennæ A₁ and A₂, hereinafter to be called, respectively, the main and auxiliary transmitting antennæ, (the waves being similarly designated and distinguished) are received respectively by main and auxiliary receiving antennæ A'₁ and A'₂, antenna A'₁ also receiving the normally received wave from a distant source. It is the purpose of the invention to combine the main and auxiliary waves received from the local transmitting station in such manner that they neutralize and produce no effect in the hybrid coil, whereas the normally received wave from the distant station, which is received by only one of the receiving circuits, is transmitted after detection through the hybrid coil in the usual manner.

A ready solution of the problem is found by producing in the two waves radiated from the local transmitting antennæ, modulations having identical frequencies, wave forms and phases. Since the carrier frequencies are not identical and, in fact, have no predetermined or fixed relation to each other, a balance must necessarily be effected between the modulating, or audio, frequency components. To this end the received waves are detected by detecting tubes or devices D₁ and D₂, in the output circuits of which will accordingly appear a wave of audio frequency together with higher frequency waves, which latter are effectually suppressed by low pass filters FL, which permit the audio frequency waves to pass. The amplitude of the voice frequency wave derived from the auxiliary antenna is, by means of amplifier AM₁, caused to be the same as that transmitted to the other antenna, and these two voice frequency waves are finally superposed in an opposing sense in the device AM₂ which may function additionally as an amplifier, as is indicated in the drawing. The received wave from the distant station is detected by the device D₁ in the usual manner and is transmitted through filter FL and device AM₂ to the hybrid coil. Although there have been shown low pass filters between the detecting tubes and the amplifier AM₂, these filters are not essential to the functioning of the system of the invention, and have been added merely to eliminate disturbance in the telephone receivers, inasmuch as the higher frequencies resulting from detection, may, in

particular cases, depending upon the relation of the carrier frequencies, produce a beat note having audio frequency in the output circuit of the device AM_2 . It should also be understood that although it has been assumed that vacuum tube devices have been used throughout the system, the invention is not dependent in any way on the use of particular types of modulating, detecting and amplifying devices, and should not be considered as so limited.

Referring now to the modification illustrated by Fig. 2, which is especially adapted for telegraphic transmission, the system shown is seen to have many features in common with the more general system illustrated in Fig. 1, these features being similarly designated, and not requiring special explanation. The system of Fig. 2 differs from that of Fig. 1 principally in the use of a common source of main and auxiliary carrier waves to insure that the frequencies of these waves have a fixed and constant relation to each other, and also that one shall be a multiple of the other, the two waves accordingly being readily convertible by the use of known means into waves of the same frequency.

The arrangement for deriving the main and auxiliary carrier waves consists of an overloaded repeating tube fed by generator G . By virtue of abnormal loading, a tube used in this manner can be caused to function as a harmonic generator. A harmonic generator of this type is described in some detail in British Patent 142,571. The circuits for this, as well as the other elements of the system are shown in Fig. 3, and only brief mention of them will be made here.

The output energy from the generator HG is divided and delivered to the modulators M_1 and M_2 in two portions. Filters F_1 and F_2 are used in order to insure that current having only the desired frequencies shall flow in the circuits of which they form a part. For example, the frequency of the currents delivered to modulator M_2 is preferably made to correspond to the fundamental frequency of the output current from generator HG , while the current delivered to modulator M_1 has a frequency corresponding to the first even harmonic of this fundamental. Since the fundamental frequency of the output current of HG is the same as the frequency of generator G , an alternative arrangement would be that in which the input energy to modulator M_2 is taken directly from the output of generator G . The filters F_1 and F_2 may be of the well known Campbell type fully described in Patent No. 1,227,114, patented May 22, 1917. The circuits of one form of this filter are shown in Fig. 3. The carrier waves obtained in the manner described above are modulated in the same manner as in the sys-

tem of Fig. 1, and the modulated carrier waves are radiated from antennæ A_1 and A_2 . In this system, as well as in the other, the antennæ, both transmitting and receiving, are tuned to the particular carrier frequency used.

The modulated carrier waves transmitted by the main and auxiliary transmitting antennæ A_1 and A_2 are received, respectively, on main and auxiliary receiving antennæ A'_1 and A'_2 . The wave received by antenna A'_1 may, in accordance with conventional practice, be considered as made up of three components; an unmodulated carrier frequency component having frequency P , and the upper and lower sidebands having frequencies respectively equal to $P+S$, and $P-S$, S being used to represent the frequency of the telegraph or other modulating wave and P to represent the carrier frequency. The corresponding frequencies of the wave received by antenna A'_2 are $\frac{1}{2}P$, $\frac{1}{2}P+S$, and $\frac{1}{2}P-S$. Since this modification embodies the idea of a high frequency balance as distinguished from low or audio frequency balance, the two high frequency waves must be identical at the balancing means and this requires that both the modulation frequencies and the carrier frequencies should be equal in the two waves. The former have been made equal by the use of a common modulating source of frequencies. The latter are made equal by the use in a particular way of the detector D_3 in the auxiliary receiving circuit.

According to theory which is well understood in the art, the detecting operation results in a complex wave consisting of separable components having frequencies equal to the sum and difference frequencies of the currents impressed on the input of the detector, as well as other components having frequencies which are double the impressed frequencies. Since currents of frequencies $\frac{1}{2}P$, $\frac{1}{2}P+S$ and $\frac{1}{2}P-S$ are impressed on the input of detector D_3 , the output current will include the component currents of frequencies P , $P+S$ and $P-S$, $P+2S$ and $P-2S$, all having a frequency comparable with frequency P . The band filter FB is designed to pass currents of frequencies P , $P+S$ and $P-S$ and suppress currents of frequencies $P-2S$ and $P+2S$. Accordingly, the wave transmitted to amplifier AM_1 has the form of the wave transmitted from the antenna A_1 and received by antenna A'_1 . This wave is amplified by device AM_1 and superposed in device AM_2 in an opposing sense with the wave received by A'_1 , as has been described with reference to Fig. 1. It should be noted that the system of Fig. 2 is especially adapted for a mode of operation in which there is a constant modulating frequency as, for example, in telegraphy, in which case the band filter FB is capable

of discriminating between $P \pm S$ and $P \pm 2S$. In the case of telephony complete discrimination is impossible for obvious reasons. Accordingly, in the case of telephony there will be an incomplete balance and some degree of side tone will be heard in the receiver. However, since the unbalanced component is of a double frequency and doubles with each passage of the high frequency circuit, the local transmitting and receiving circuits will not sing.

In Fig. 3 there has been shown a detailed circuit arrangement in which the system illustrated schematically in Fig. 2 may be embodied. The circuit details corresponding to the several elements are conventionally shown and do not require further explanation. It should be understood, however, that these circuit arrangements are illustrative only, and that any one of the various arrangements commonly used is equally adaptable to the system and other amplifying, detecting, generating means, etc., may be used. In this figure, elements are designated similarly to corresponding elements in Fig. 2 and are similarly arranged, the only exceptions being amplifier AM, and high pass filter FH, which are shown in inverse relation.

It is to be noted that the two systems shown have in common the idea of transmitting from the main and auxiliary antennae of the local transmitting station radically different amounts of power at radically different frequencies, the main carrier wave energy being intended for distant reception, and the auxiliary carrier wave energy for nearby or local reception, and of balancing out at the nearby point such of the main carrier frequency energy as may be there received. Although systems to accomplish the purpose sought have been disclosed in detail, it should be understood that the invention is broadly as expressed above, and accordingly should not be construed as limited in any way to the specific arrangement shown, but only by the appended claims.

What is claimed is:

1. The method of preventing side tone interference in a duplex radio signaling system which comprises radiating an auxiliary wave of different frequency from the main radiated wave and balancing out by said auxiliary wave at the local receiving station, such of the main radiated wave as may be there received.

2. The method of preventing side tone interference in a duplex signaling system which comprises radiating to the receiving station a wave of the same modulating characteristic as the normally transmitted wave, but having a different carrier frequency, resonantly receiving said wave at the receiving station, converting it to a wave identical with the normally transmitted wave, and

balancing out with said converted wave that portion of the normally transmitted wave which is incident on the receiving station.

3. The method of preventing side tone interference in a duplex radio signaling system arranged for non-directive transmission and reception, which comprises separately radiating an auxiliary wave, separately receiving said wave, and balancing out thereby at the receiving station such portion of the interfering energy as may be received at said station by combining said auxiliary received wave therewith in an opposing sense.

4. The method of preventing side tone interference at the receiving station of a related pair of non-directive transmitting and receiving stations in a duplex radio communicating system which consists in non-directively receiving an auxiliary wave at said receiving station and balancing out the interfering wave by combining therewith said auxiliary wave.

5. The method of preventing side tone interference in a duplex radio signaling system which comprises radiating a main wave modulated in accordance with signals, radiating an auxiliary modulated carrier wave of low power and frequency as compared with the main wave and modulated in the same manner, receiving said auxiliary wave, detecting the same, selecting from the detected wave that component which has the same frequency and wave form as the said main wave, and combining in an opposing sense said component amplified to the proper degree with such portion of the main transmitted wave as may be received at the related receiving station, whereby said last mentioned wave portion is effectually balanced out.

6. The method of preventing side tone interference at the receiving station of a related pair of transmitting and receiving stations in a duplex radio communicating system which consists in generating a main carrier wave, generating an auxiliary wave, said auxiliary wave having a frequency which is a subharmonic of the frequency of said main wave, modulating each of said waves in accordance with signals, resonantly receiving said modulated wave, detecting said modulated auxiliary wave, selecting from the detected wave that component which has the same frequency and wave form as the said main modulated wave, and combining in an opposing sense said component, amplified to the proper degree, with such portion of the main modulated transmitted wave as may be received at the related receiving station, whereby said last mentioned wave portion is effectually balanced out.

7. A station of a duplex radio system comprising in combination, means for trans-

- mitting a modulated radio carrier wave, means for radiating an auxiliary wave of different frequency, means for receiving modulated carrier waves from a distant station, means for receiving said radiated auxiliary wave, and means using said radiated auxiliary wave for balancing out such portion of the normally transmitted wave from the same station as is incident on said receiving means.
8. In a communicating station of a duplex radio system adapted for modulated carrier wave transmission, the combination with transmitting and receiving circuits for modulated waves, of separate means associated with said circuits for transmitting and receiving an auxiliary wave having equivalent modulation characteristics, and further means associated with said receiving circuit for combining said received auxiliary wave in an opposing sense with such portion of the modulated transmitted wave as may be there received to balance out the latter.
- 25 9. In a communicating station of a duplex radio system adapted for modulated carrier wave telephony, the combination with normal transmitting and receiving circuits for modulated carrier waves, of means associated with said circuits for transmitting and receiving an auxiliary wave having equivalent modulation characteristics, and a frequency which is a subharmonic of the normal carrier frequency means associated with said receiving circuit for converting said auxiliary wave to a wave identical in frequency and form with the normally transmitted wave, and means for combining said converted auxiliary wave in an opposing sense with such portion of the normally transmitted wave as may be received at said receiving circuit.
10. A communicating station of a duplex radio system provided with means for preventing side tone interference comprising a main transmitting antenna, an auxiliary transmitting antenna, means for the radiating from said antennæ equivalent modulations on two different carrier frequency waves, the wave having the lower frequency being radiated from said auxiliary antenna, a receiving antenna, an auxiliary receiving antenna, means in circuit with one of said last mentioned antennæ to change the carrier frequency of the wave thereby received to a frequency equivalent to that received by the other receiving antenna, and means for equalizing and opposing the received waves, whereby the effect of the wave received from said main transmitting antenna is effectually balanced out.
- 15 11. A communicating station of a duplex radio system comprising a related pair of transmitting and receiving stations, the former of which comprises in combination, a main antenna, an auxiliary antenna arranged to transmit low power waves and tuned to a lower frequency than said main antenna, modulating means in circuit with each of said antennæ, a harmonic generator, 65 said generator constituting a source of high frequency carrier waves for said modulators, means connecting each of said modulators with said generator and adapted to permit only currents of a selected harmonic, different from that selected for the other circuit, to flow to said modulators, and a common modulating source for said modulators; and the latter of which comprises, in combination, a main receiving antenna and an auxiliary receiving antenna, tuned respectively to the main and auxiliary transmitting carrier frequencies, a vacuum tube device and an amplifying device both in circuit with said auxiliary receiving antenna and adapted 70 to equalize the frequency and amplitude of the modulated carrier wave received by said auxiliary receiving antenna with the corresponding wave in the main receiving antenna circuit, and means for combining said waves in an opposed sense, whereby such portion of the main transmitted wave as may be received on the main receiving antenna is 75 effectually balanced out.
- 20 12. The combination as specified in claim 95 11, having a detecting means in circuit with said combining means whereby the normally received waves may be received and detected.
- 25 In witness whereof, I hereunto subscribe my name this 21st day of December, A. D. 100 1920.

JOHN MILLS.
